UNITED STATES PATENT OFFICE.

GEORGE H. GILMAN, OF BOSTON, MASSACHUSETTS.

HEAT TREATING ARTICLES.

Application filed September 21, 1920. Serial No. 411,762.

My invention relates to apparatus for radiating arms 11, these arms carrying pusher elements 12 which are provided with heads 13 for contacting the side of the legs 5 of the carrier. As will be readily understood, when the shaft 10 is revolved, the pusher elements cause the carriers to move around the track. For preventing the tendency of the pusher elements to cause the carrier and its wheels to tilt, I provide the 60 roller 14 which travels along a guideway or track formed by a portion of the plate between the tracks 2 and 3, the roller being supported by the brackets 15 and 16 carried by the legs 6.

My invention will be best understood from the following specification and accompanying drawings of a specific embodiment 10 thereof submitted for illustrative purposes, while the scope of my invention will be particularly pointed out in the appended claims.

In the drawings:

15 Fig. 1 shows a drill steel carrier and parts of a heat treating machine cooperating therewith;

Fig. 2 is an elevation of the carrier looking at Fig. 1 from the right;

20 Figs. 3, 4, 5, 6 and 7 respectively are sections on the lines 3—3, 4—4, 5—5, 6—6 and 7—7 of Fig. 1;

Fig. 8 shows on an enlarged scale the position of the parts when the gripping device is in open position;

Fig. 9 is a view corresponding to Fig. 8 with the gripping device in closed position; and

Fig. 10 is a more or less diagrammatic view showing parts of the heat treating machine cooperating with the carrier.

As the details of the heat treating apparatus in general form no part of my present invention, the same will not be described except to show how the same cooperates with the invention claimed herein. Referring particularly to Figs. 1, 2 and 10, such machine comprises a plate 1, bent to form a closed cylinder and provided at its 35 upper and lower portions with guideways in the form of tracks 2 and 3. Straddling the plate is a carrier for the drill steel 4, said carrier comprising the legs 5 and 6 and a portion 7 connecting the upper ends of the legs. To the leg 6 is secured the drill steel and supported by the leg 5 are the wheels 8 and 9 which roll along the tracks. 40

The tracks just described are undulated in order to lower and raise the end of the 45 drill steel in and out of the several instrumentalities for treating the end of the drill steel, for example a furnace and a quenching tank. For moving the steel I have shown the tracks mounted concentrically with the shaft 10 and carried by the latter and for rotation therewith, I provide the 50

For removably securing the drill steel to the carrier I provide the clips 17 and 18 and in addition thereto and for the same purpose, a gripping device which also prevents the steel from sliding downwardly through 75 the clips. In order to accurately position the steel on the carrier, the clip 17 is made in the form of a spring, while the clip 18 is formed of such dimensions as to be non-yieldable.

The gripping means hereinbefore referred to as preventing the steel from sliding through the clips comprises a rock shaft 19 carrying the levers 20 and 21, said levers embracing the leg 6 and the rock 85 shaft being pivotally supported on said leg by causing the rock shaft to fit semi-cylindrical bearing recesses formed respectively in the leg and by the bent portion 24 of the bearing cap 25, the latter being secured to 90 the leg by means of the bolts 26. Carried by the lever 20 is a jaw 27 preferably pivotally supported on the lever by means of the pin 28 and to prevent excess movement of the jaw on the pin I preferably recess the 95 end portion of the jaw to form the stop surfaces 29, 30, 31 and 32 which cooperate with the projecting ends 33 and 34 of a transverse pin to prevent in an obvious manner such excess movement. Preferably the 100 rock shaft is biased to carry the jaw into the position illustrated by Fig. 9, in which position it will be appreciated that the tendency of the steel to move downwardly under the influence of gravity causes the 105 jaw to tightly bind against the steel. To this end I provide a plunger 35 slidably mounted in ears 36 carried by the leg 6 of the carrier and cooperating with the plunger I provide a spring 37 having at one 110 end an abutment 38 carried by the leg and at its other end an abutment provided by the

shoulder 39 formed by the reduced portion 40 of the plunger. The end of the plunger slidably contacts the upper surface of the lever 20 and exerts thereon a force tending 5 to turn the lever into the position illustrated by Fig. 9.

As illustrated by Fig. 8, when the lever 20 is moved upwardly the steel may be disengaged from the carrier, and when it is 10 in the position illustrated by Fig. 9, the removal of the steel from the carrier is prevented. To prevent the turning of the rock shaft from affecting the position of the steel and for providing an abutment for 15 the steel acting in the opposite direction to the jaw 27, the end 41 of the rock shaft to the right of the lever 20 as viewed in Fig. 5 is offset and cut away to form the surfaces 43. By this means, the portion of 20 the rock shaft adjacent the intersection of the surfaces 43 is always in contact with the steel and without causing movement of the rock shaft to affect the position of the steel.

25 For operating the rock shaft to engage and disengage the jaw with the steel I provide the members 44 providing the stationary cam surfaces 45 and 46, these members being so located to position the cam surfaces 30 45 and 46 in the path of the lever 21 carried by the rock shaft. When the carrier is moved and the lever strikes the surface 45 it travels up the same and slides across the cam surface 46 as illustrated by Figs. 2, 4 35 and 7. This moves the jaw from engagement with the steel and when the lever reaches the end of the surface 46, the plunger 35 immediately moves the lever 20 downwardly to turn the rock shaft to carry the 40 jaw into engagement with the steel.

Referring particularly to Figs. 1, 2 and 10 in my machine I provide a platform 47 which I term the loading station, in front of which is located one of the cam members 45 44 so that when the carrier passes by the station the gripping member is open. As the carrier passes this station the operator places the end of the steel on the platform and slides it into engagement with the spring 50 clips and as the carrier leaves the station the lever 21 reaching the end of the cam surface 46 causes the gripping device to close and securely fasten the steel to the carrier. The carrier now passes around the track 55 through the various instrumentalities of the machine for treating the steel and finally reaches the platform 48 which I term the discharging station where is located a similar cam member 44 which opens the gripping 60 device to permit the steel to be removed from the carrier.

Although I have described one specific embodiment of my invention, it is to be understood that I am not limited thereto and 65 that extensive deviations may be made with-

out departing from the spirit of my invention.

Claims:

1. A machine for heat treating drill steels having, in combination, a heater, a quenching tank, drill steel presenting means traversing said heater and tank and successively presenting the end portions only of said steels thereto, said presenting means carrying the drill steels in vertical position by engagement therewith at points intermediate their length, said means including drill steel gripping devices having open positions for removal of the treated steels and reception of new steels and closed positions for engaging the steels, and means independent of the drill steels for placing said gripping means in open position for removal of the steels after the steels have been presented to the quenching tank and thereafter causing them to close prior to presenting newly inserted steels to the heater. 70

2. A machine for heat treating drill steels having, in combination, a heater, a quenching tank, drill steel presenting means traversing said heater and tank and successively presenting the end portions only of said steels thereto, said presenting means carrying the drill steels in vertical position by engagement therewith at points intermediate their length, said means including drill steel gripping devices having open positions for removal of the treated steels and reception of new steels and closed positions for engaging the steels, and means independent of the drill steels responsive to motion of said presenting means for placing said gripping means in open position for removal of the steels after the steels have been presented to the quenching tank and thereafter causing them to close prior to presenting newly inserted steels to the heater. 90

3. A machine for heat treating drill steels having, in combination, a heater, a quenching tank, drill steel presenting means traversing said heater and tank and successively presenting the end portions only of said steels thereto, said presenting means carrying the drill steels in vertical position by engagement therewith at points intermediate their length, said means including drill steel gripping devices having open positions for removal of the treated steels and reception of new steels and closed positions for engaging the steels, and means independent of the drill steels including a stationary cam for placing said gripping means in open position for removal of the steels after the steels have been presented to the quenching tank and thereafter causing them to close prior to presenting newly inserted steels to the heater. 110

4. A machine for heat treating drill steels having, in combination, a heater, a quenching tank, drill steel presenting means trav-

- ersing said heater and tank and successively presenting the end portions only of said steels thereto, said presenting means carrying the drill steels in vertical position by engagement therewith at points intermediate their length, said means including drill steel gripping devices having open positions for removal of the treated steels and reception of new steels and closed positions for engaging the steels, a loading table traversed by said presenting means and upon which the steels may be stood on their ends to be treated for gauging their position relative to said means, means independent of the steels for causing said gripping means to be in open position when at said loading table and to close prior to leaving said loading table and for removing the steels from said gripping means after the steels have been quenched.
5. A machine for heat treating drill steels having, in combination, a heater, a quenching tank, drill steel presenting means traversing said heater and tank and successively presenting the end portions only of said steels thereto, said presenting means carrying the drill steels in vertical position by engagement therewith at points intermediate their length, said means including drill steel gripping devices having open positions for removal of the treated steels and reception of new steels and closed positions for engaging the steels, a loading table traversed by said presenting means and upon which the steels may be stood on their ends to be treated for gauging their position relative to said means, means independent of the steels for causing said gripping means to be in open position when at said loading table and to close prior to leaving said loading table and for opening said gripping means after the steels have been quenched.
6. A machine for heat treating drill steels comprising, in combination, a heat treating instrumentality, means for presenting the ends only of drill steels to said instrumentality and removing them therefrom comprising a plurality of drill steel carriers movable independently of each other, drill steel gripping means for each carrier, means for supporting said carriers and moving them past a drill steel manipulating station, and means acting independently of the presence of drill steels and responsive to motion of said carriers for causing said gripping means to be opened when said carriers are at said station and to be closed when they leave said station.
7. A machine for heat treating the ends of rod like articles, having in combination, a plurality of article carriers movable independently of each other, article gripping means for each carrier, supporting means for said carriers, means for moving said carriers by an article manipulating station, and means acting independently of the presence of an article and responsive to motion of said carriers for causing said gripping means to be open when said carriers are at said station and to be closed when said carriers leave said station.
8. In a machine for heat treating the ends of rod-like articles, a plurality of independent carriers for said articles, supporting means for said carriers, means for moving said carriers relatively to said supporting means, means for securing such articles to said carriers and in a vertical position, and means responsive to the motion of said carriers for operating the means for securing articles to the carriers independently of the presence of articles on said carriers.
9. In a machine for heat treating the ends of rod-like articles, a plurality of independent carriers for said articles, supporting means for said carriers, means for moving said carriers relatively to said supporting means, gripping means carried by said carriers and for engaging such articles when presented in vertical positions to said carriers, and means responsive to motion of said carriers for operating said gripping means independently of the presence of articles on said carriers.
10. In a machine for heat treating the ends of rod-like articles, a plurality of independent carriers for said articles, a loading platform or the like, supporting means for said carriers, means for moving said carriers relatively to said supporting means to and from said platform, means for securing such articles to said carriers, and automatic mechanism for causing said means to be open to receive said articles when said carriers are at said platform and to cause said articles to be secured to said carriers when they leave said platform.
11. In a heat treating machine for drill steels, a closed track, means for conveying a drill steel along said track, releasable means for holding a drill steel to said first means, and automatic means for causing said releasable means to be inoperative for holding said steel when said means for conveying the drill steel is in a definite relation with said track and for causing it to be operative when in another definite relation.
12. In a heat treating machine for drill steels, a closed track, a plurality of carriers for said drill steels and mounted on said track, means for propelling said steels about said track, means carried by said carriers for securing a drill steel thereto, mechanism responsive to motion of said carriers and for operating said means, and said mechanism being so arranged as to cause a steel to be secured to said carrier while passing over the major portion of said track and for other portions rendering said means inoperative.
13. In an article carrier, a movable mem-

- ber for gripping an article, and a support for said member so arranged that movement of said article tends to force said member against the article.
- 5 14. In an article carrier, a member having a jaw carried thereby for relative movement thereto, and means providing a support for said member and so arranged that movement of the article tends to move said member 70 to force the jaw against the article.
- 10 15. In an article carrier, a lever having a support at one side of the article and adapted to be inclined downwardly to a point on the opposite side of said article, and a jaw for gripping the article and carried by the lever at such point.
- 15 16. In an article carrier, a movable member for gripping an article, a support for said member so arranged that movement of 75 said article tends to force said member against the article, and means for moving said member away from the article.
- 20 17. In an article carrier, a movable member for gripping an article, a support for 80 said member so arranged that movement of said article tends to force said member against the article, and means normally biasing said member toward gripping position.
- 25 18. In an article carrier, a movable member for gripping an article, a support for 85 said member so arranged that movement of said article tends to force said member against the article, and means for moving said member into and out of gripping position.
- 30 19. In an article carrier, a member having a jaw carried thereby for relative movement thereto, means providing a support for said member and so arranged that movement 90 of the article tends to move said member to force the jaw against the article, and means for moving said member into and out of gripping position.
- 35 20. In an article carrier, a lever having a support at one side of the article and adapted to be inclined downwardly to a point on the opposite side of said article, a jaw for gripping the article and carried by the lever at such point, and means for moving said lever 95 to carry the jaw into and out of gripping position.
- 40 21. In an article holder, a rock shaft, a lever carried thereby, a gripping member carried by said lever in spaced relation to 100 said shaft whereby an article may be inserted in such space, and a support for said rock shaft permitting said shaft to be turned to bring said member against such article when so inserted.
- 45 22. In an article holder for carrying articles tending to fall therefrom by gravity, means affording an abutment for said articles, a jaw carried in spaced relation to said abutment, and a support for said jaw adjacent 105 said abutment and so located to permit the jaw to be moved downwardly to bring it into gripping position.
- 50 23. In an article carrier, a plurality of means for holding an article on said carrier, one of said means comprising a member for 110 gripping such article, and a support for said member so arranged that movement of said article tends to force said member against the article.
- 55 24. In a machine of the character described, an article carrier, a rock shaft carried thereby, a lever carried by said shaft, a jaw pivoted to said lever in spaced relation to said shaft whereby an article may be inserted in such space, and automatic means 115 for turning said rock shaft to move the jaw into and out of position to engage such article whereby to permit the insertion and removal of such article and to secure it to the carrier.
- 60 25. In a heat treating machine, a carrier for drill steels, means for securing a steel to said carrier at spaced points, one of said means being arranged to tightly grip said steel, and automatic mechanism for causing 120 said last named means to grip a steel and to release it.
- 65 26. In a heat treating machine for drill steels, a carrier for said steels, a rock shaft supported by a carrier, a lever carried by 125 said rock shaft, a jaw carried by said lever, means for positioning a drill steel between said jaw and said shaft, and a spring for forcing said rock shaft to turn, whereby said steel is held between said shaft and said 130 jaw.
- 70 27. In a heat treating machine for drill steels, a carrier for such steels, means for moving said carrier, a means for gauging the position of said steels on said carrier, means for holding the steel to said carrier when the steel is presented thereto, and other means actuated by motion of said carrier for causing said steel to be secured to the carrier after the steel is presented thereto.
- 75 28. In a machine for heat treating drill steels, a track, a carrier having a wheel engaging said track, means engaging said carrier at the side of said track for pushing it along the track, and means preventing 135 tilting of said wheel.
- 80 29. In a machine for heat treating drill steels, a carrier, a guideway supporting said carrier for movement therealong, means at the side of said guideway for pushing said carrier, a second guideway and means carried by said carrier cooperating with said second guideway for preventing tilting of the carrier.
- 85 30. In a machine for heat treating drill 140 steels, an article carrier, a pair of guideways for supporting said carrier and permitting movement therealong of said carrier, means at the side of said guideway for pushing said carrier, a third guideway intermediate the

- two first mentioned, and means supported by said carrier cooperating with said third guideway for preventing tilting of the carrier on said pairs of guideways.
- 5 31. In a machine of the character described, a track, a carrier supported by said track, means at the side of said carrier for pushing said carrier along said track, and guiding means neutralizing the tendency of said first 10 mentioned means to tilt the carrier.
32. In a machine of the character described, a pair of spaced tracks, an article carrier having a pair of legs straddling one of said tracks, wheels carried by one of said 15 legs and engaging said tracks, means cooperating with the other leg for forcing the carrier to move along the tracks, and means for neutralizing the tendency of the first named means to tilt the carrier.
- 20 33. In a machine of the character described, a pair of spaced tracks, an article carrier having a pair of legs straddling one of said tracks, wheels carried by one of said legs and engaging said tracks, means cooperating with one of said legs for forcing the carrier to move along the tracks, and means for neutralizing the tendency of the first 25 named means to tilt the carrier.
34. In a machine of the character described, a pair of spaced tracks, an article carrier having a pair of legs straddling one of said tracks, wheels carried by one of said legs and engaging said tracks, means cooperating with one of said legs for forcing 30 the carrier to move along the tracks, a third track, and means carried by one of said legs and engaging said track for neutralizing the tendency of the first named means to tilt the carrier.
35. In a machine of the character described, a pair of spaced tracks, an article carrier having a pair of legs straddling one of said tracks, wheels for supporting said carrier on said tracks, means cooperating with one of said legs for forcing the carrier to move 40 along the tracks, a third track, and means carried by one of said legs and engaging said track for neutralizing the tendency of the first named means to tilt the carrier.
36. In a machine of the character described, a carrier, spaced guideways for said carrier, means for pushing said carrier along said guideways, and a third guideway cooperating with said carrier in such wise as to neutralize the tendency of said means to tilt 45 said carrier.
37. In a machine of the character described, a cylindrical plate, a carrier having legs straddling said plate, wheels on said carrier and riding on the upper and lower edges 50 of said plate, means for forcing said carrier to move circumferentially about said plate, and a third wheel for said carrier and so positioned as to ride on the lateral surface of said plate and neutralize the tendency of 55 said carrier to tilt.

In testimony whereof, I have signed my name to this specification.

GEORGE H. GILMAN.
